UNITED STATES PATENT OFFICE.

FRANCIS X. RETTENMEYER, OF MONTCLAIR, NEW JERSEY, ASSIGNOR TO WESTERN ELECTRIC COMPANY, INCORPORATED, OF NEW YORK, N. Y., A CORPORATION OF NEW YORK.

AMPLIFYING CIRCUITS.

Application filed May 11, 1926. Serial No. 108,239.

This invention relates to amplifying systems and more particularly to energizing circuits for space discharge amplifiers.

An object of the invention is the suppression in the output circuits of space discharge devices, such as amplifiers, of noise currents due to voltage ripples that may be unavoidably present in the continuous voltage of the energizing source.

10 To accomplish the suppression of the noise currents use is made of a circuit arrangement similar in certain respects to that disclosed in U. S. Patent No. 1,541,311, issued June 9, 1925, to S. E. Anderson, but which is an improvement thereover, whereby smaller and less expensive impedance elements may be used to secure the desired result.

An additional feature of the invention permits both the filament and the space path of 20 an amplifier to be energized from the same source, a single compensating arrangement serving to suppress the noise currents due both to the effect of the ripple voltage in the space circuit, and to the presence of the ripple current in the filament.

These and other features of the invention are more clearly set forth in the following detailed description of the invention and of its mode of operation. In the drawing, which 30 forms part of the description,

Fig. 1 shows in schematic form a simple amplifier circuit illustrating the improved arrangement for neutralizing the effects of a noise producing ripple; and

35 Fig. 2 shows in more complete schematic form a detecting and amplifying system embodying the several features of the invention.

In Fig. 1 a three electrode space discharge device 1 is furnished with space current from 40 a power source 2, which may be an A. C. rectifier, or a direct current generator or other source of direct current, the voltage of which is subject to more or less periodic fluctuations.

45 The circuit is adapted for amplifying signal waves which are received by input transformer 3, and which, after amplification, are transmitted by output transformer 4. Across

the terminals of the source 2 are connected in series two impedance networks, one of which 50 comprises a parallel combination of resistance R_1 and capacity C_1 , and the other of which comprises a resistance R_3 in parallel with a series combination of a resistance R_4 and a capacity C_3 .

The anode of the discharge device is connected through the primary winding of output transformer 4 to the positive terminal of source 2, to which also is connected one terminal of the network R_1 , C_1 . The control electrode of the discharge device is connected through the secondary winding of transformer 3 to the junction point of resistance R_4 and capacity C_3 in the second network, and the cathode is connected to the junction point 65 of the two networks.

Current from source 2 divides between the space path and the path containing network R_1 , C_1 , the two currents combining again at the junction point of the two networks and 70 the cathode, and flowing together through network R_3 , R_4 , C_3 .

It is necessary that a steady space current should flow in the space path of the discharge device. It is therefore desirable that the ripple component be suppressed in that path to prevent it appearing as a source of noise in the output circuit of the discharge device. The suppression of the ripple current in the space path is effected by impressing oppositely phased ripple E. M. F.'s upon the grid and the plate of the discharge device, the relative values of the opposing E. M. F. being determined by the amplification constant of the device. The potential impressed upon the plate of the discharge device from source 2 is determined largely by the impedance of network R_1 , C_1 and the internal resistance of the discharge device, which will be denoted by R , while the potential impressed upon the grid is equal to the fall of potential in capacity C_3 due to the current traversing the network R_3 , R_4 , C_3 .

If the total current, including both the steady current and the ripple component, delivered by source 2 be denoted by I_0 , then the

E. M. F. denoted by E_c , impressed upon the grid, is given by the formula

$$5 \quad E_c = -I_o \frac{R_3 Z_3}{R_3 + R_4 + Z_3}$$

$$= -I_o \frac{R_3}{R_3 + R_4} \cdot \frac{Z_3(R_3 + R_4)}{R_3 + R_4 + Z_3} \quad (1)$$

in which Z_3 is the impedance of capacity C_3 .
10 The factor

$$\frac{R_3}{R_3 + R_4}$$

15 is a simple numerical quantity, which may be denoted by n , and the factor

$$\frac{Z_3(R_3 + R_4)}{R_3 + R_4 + Z_3}$$

20 represents an impedance constituted by capacity C_3 in parallel with a resistance equal to the sum of R_3 and R_4 .

Evidently the network $R_3 R_4 C_3$ might be replaced by a network wholly included in the 25 path between the cathode and point of connection to the grid lead, and comprising a larger capacity, equal to nC_3 , in parallel with a resistance equal to n times $(R_3 + R_4)$.

The fraction of the total current I_o that 30 flows through the space path may be denoted by I_2 and is found to be in accordance with the equation

$$35 \quad I_2 = \frac{\frac{Z_1 R_1}{Z_1 + R_1} - n \mu \frac{Z_3(R_3 + R_4)}{R_3 + R_4 + Z_3}}{R + \frac{Z_1 R_1}{Z_1 + R_1} + Z_r} \quad (2)$$

in which Z_r is the load impedance introduced 40 into the circuit by transformer 4; Z_1 is the impedance of capacity C_1 , and μ is the amplification constant of the vacuum tube.

Since the terms

$$45 \quad \frac{Z_1 R_1}{Z_1 + R_1} \text{ and } n \frac{Z_3(R_3 + R_4)}{R_3 + R_4 + Z_3}$$

both represent impedances of the same type 50 it is possible to construct the network so that these terms are equal at all frequencies, in which case no current flows in the space path.

55 Considerations of transmission of the amplified signal waves require that a low impedance return path for the output waves be provided between the cathode and the terminal of the primary winding of the output transformer. Such a path is provided by condenser C_1 the magnitudes of which should be large enough to make its reactance about one tenth of the internal resistance R of the 60 vacuum tube. If speech frequencies are transmitted the effective capacity of C_1 may be about one or two microfarads, and for higher frequencies correspondingly smaller capacities may be used.

If a simple combination of resistance and capacity were included in the grid circuit to balance the impedance of the $C_1 R_1$ combination it would require a capacity μ times as large as C_1 , and with many types of vacuum tubes the value of the grid circuit capacity 70 might be as high as 6 to 12 microfarads, or even greater.

By using the arrangement of the invention, however, it is possible to balance the capacity C_1 by means of a relatively small capacity equal to $n \times \mu$ times C_1 , n being the 75 ratio

$$\frac{R_3}{R_3 + R_4},$$

80

which is less than unity, and which may be made as small as desired by the proper choice of resistances R_3 and R_4 .

The establishment of an exact balance between the E. M. F. impressed upon the grid 85 and the plate from source 2 has the desirable effect of eliminating the ripple component from the space current, but it also has the effect of reducing the steady space current to zero. It is therefore necessary to upset the 90 balance to some extent in order that a steady space current may flow. This may be done by inserting a low voltage battery 5 in the grid circuit, the battery being poled to impress a positive E. M. F. upon the grid, or, alternatively, it may be accomplished by increasing 95 the resistance R_1 to a value greater than that required for a complete balance.

The first method of upsetting the balance does not result in the introduction of any noise 100 producing current in the space path, and, for circuits in which complete suppression is necessary, this is the preferred method. A voltage of from 6 to 12 volts is usually all that is required, and as no current is drawn from the 105 battery it may be composed of very small dry cells.

The second method results in the introduction of a small amount of ripple current in the 110 space path, but it has been found in practice that the amount of noise resulting is negligibly small. The greatest amount of ripple, or noise current that can be introduced when the balance is upset by increasing resistance R_1 corresponds to the case in which R_1 is infinitely great, that is, when the resistance is left 115 out of the circuit entirely. For this case, the ratio of the space current to the total current is found to be

$$120 \quad \frac{I_2}{I_o} = \frac{1}{[1 + j\omega C_1 R_{10}] [1 + j\omega C_1 (R + Z_r)]}. \quad (3)$$

in which R_{10} is the value of R_1 required for complete balance.

At zero frequency this ratio is unity, but it decreases very rapidly as the frequency increases, and at the ripple frequency it may 125

readily be made less than one part in two hundred by a proper choice of constants.

In any specific case the values of the impedance elements are best determined by trial 5 using as a guide the following equations by which their relative values are expressed.

$$C_1 = \frac{1}{\mu} \left(1 + \frac{R_4}{R_3} \right) C_3, \quad (4)$$

$$R_1 = \mu R_3. \quad (5)$$

Capacity C_3 being determined by considerations of transmission efficiency the value of C_1 may be chosen at will, the principal considerations being those of size and cost. 15 Equation 4 then determines the ratio of R_4 to R_3 .

The total steady current delivered by source 20 2 is limited by resistance R_3 and the parallel combination of R_1 and the resistance of the 25 vacuum tube. When a rectifier is used as the supply source the total current that the rectifier can deliver at the operating voltage of the system determines the summation value of the resistances R_1 and R_3 , the relative values of which are determined by Equation 5.

If a grid battery is used to produce the steady current, resistances R_1 and R_3 should be exactly in the ratio determined by Equation 5. 30 If the grid battery is not used the value of R_3 should be made such that the fall of potential in it due to the total steady current is that required for the proper polarization of the amplifier grid.

35 The application of the foregoing principles in a practical system and their extension to the suppression of noise effects due to ripples in the filament current will be described in connection with the system shown in Fig. 2. Numerical values of the impedance coefficients suitable for use in circuits employing vacuum tubes of standard design will also be given. It is to be understood, however, that the invention is not limited to the 45 particular system disclosed, but only in accordance with the limitations set forth in the claims.

In the circuit of Fig. 2, vacuum tube 1 is a 50 detector receiving modulated waves through the input transformer 3, and delivering detected signal waves, corresponding to speech for example, through output transformer 4 to a low frequency amplifier 6, from which the repeated waves are transmitted through 55 transformer 7 to a telephone receiver 8. The power source is a vacuum tube rectifier 9 which is energized through transformer 10 from a source 11 of 60 cycle current.

In the specific form of the circuit chosen to 60 illustrate the computation of the numerical values, the detector tube 1 has an amplification constant equal to 6 and operates under the following voltage and current conditions: the normal filament current is 60 milliamperes, the plate voltage 100 volts, and

the negative potential of the grid required for most efficient detection, is equal to 12 volts. The space current of the detector is only a small fraction of a milliampere. The amplifier tube 6 is designed to operate at a plate potential of 350 volts, a grid potential of -15 volts, and to take a steady space current of 30 milliamperes. The amplification constant of this tube is also 6, and the filament heating current is one ampere. 75

The filament of amplifier 6 is heated by alternating current supplied to it through a balanced low voltage secondary winding 12 of the power transformer 10, the mid-point of the filament heating winding being connected to ground. 80

Rectified current is supplied to the plate circuits of the two vacuum tubes through filter 13. This current contains a steady component and ripple components, mainly of 85 120 cycles and 240 cycles, which are largely suppressed by the filter. Space current for amplifier 6 is taken directly from the output of the filter, the path followed by this current being through the primary of transformer 7, 90 the space path of amplifier 6, grounded conductor 15, the filament of detector 1, and resistances 16 and 17, to the anode of the rectifier. The space current of amplifier 6 is utilized to heat the filament of detector 1, and, in the numerical example chosen, furnishes one-half of the required heating current. The additional current required is supplied by the rectifier through resistances 14 and 18, the space current for the rectifier being also 100 furnished through resistance 14.

Resistances 19 and 20 connect the grids of tubes 6 and 1 respectively to points in the power circuit at potentials suitable to give the requisite polarizing potentials. Capacities 22 and 24 provide low impedance return paths for the output currents from the discharge tubes and capacities 21 and 23 are the balancing capacities associated with condensers 22 and 24 respectively. 105 110

In the detector circuit the elements 18, 22, 115 16, 20 and 21 correspond respectively to resistance R_1 , capacity C_1 , resistances R_3 and R_4 , and capacity C_3 of the system of Fig. 1. The vacuum tube filament is included with resistance 16 as part of the grid polarizing resistance. Fluctuations of the filament potential are therefore included in the grid E. M. F. and consequently are compensated along with the plate potential variations. 120

In the amplifier circuit condensers 23 and 125 24 correspond to capacities C_3 and C_1 of Fig. 1, and resistance 19 to R_4 , while resistances 17 and 16, the grid polarizing resistances, correspond to R_3 . In the amplifier circuit the resistance corresponding to R_1 is constituted by the two resistances 18 and 14 in series.

In the specific example, condensers 22 and 130 24 are each of 2 microfarad capacity, this being a conveniently available unit, and of

sufficiently large capacity to provide a path for the speech waves of impedance less than 1000 ohms at all frequencies above 100 cycles. Resistances 16 and 17, each carrying a current of 60 milliamperes, are proportioned to provide negative polarizing potentials of 12 and 15 volts on the grids of tubes 1 and 6 respectively. This fixes the value of resistance 16 at 200 ohms and of resistance 17 at 50 ohms.

10 Resistance 20 may be fixed arbitrarily at such a value as will make the proper capacity of condenser 21 a convenient value. In the circuit illustrated account must be taken of the fact that the current in the grid network 15 is twice that in the plate circuit network, consequently condenser 20 should have twice the capacity determined in accordance with equation 5. Appropriate co-related values for resistance 20 and condenser 21 are 10,000 ohms 20 and 0.5 mfd. respectively.

Resistances 18 and 14 are proportioned by trial, their proper values being such as will permit the required filament current to flow and at the same time provide the proper plate 25 potential for detector 1. For the particular circuit illustrated values of 2000 ohms and 8500 ohms respectively are found to be suitable. By similar procedures the values of resistance 19 and capacity 23 are established 30 at 10,000 ohms and 0.3 mfd. respectively.

The proportions of the impedances in the energizing circuit as determined in this way leave a certain amount of the ripple current flowing in each plate circuit. This is due in 35 part to the unbalancing of the circuit necessary to permit the flow of the steady space currents and in part to the interlinking of the energizing circuits of the two vacuum tubes. In addition there is also a certain amount of 40 120 cycle current introduced into the output current of amplifier 6 by the alternating current used to heat the filament.

In most cases it is possible to neutralize to some extent the residual noise currents that 45 are present in the system when the impedances have the computed values. The poling of the windings of transformer 4 may be arranged so that the unbalanced current in the plate circuit of the detector when repeated by amplifier 6 opposes the unbalance current in the amplifier output circuit. In addition one or more of the energizing circuit impedances, for example condensers 21 and 23, may be made adjustable, whereby the unbalanced current 50 in the circuit of the one vacuum tube may be increased or decreased to secure the greatest degree of over all neutralization.

What is claimed is:

1. In a wave transmission system, a three 60 electrode space discharge device, a source of space current therefor having an undulatory E. M. F., impedance means for impressing the E. M. F. of said source upon the space dis-

charge path of said device, and means for preventing the flow of undulatory current in the space path of the discharge device, said means comprising an impedance network which is connected between the cathode of the space discharge device and the negative terminal of the current source, and which is constituted by a resistance element having in parallel therewith a resistance element in series with a condenser, and a connection from the control electrode of said device to the junction point of said condenser and said series resistance. 65 70 75

2. In combination, a three-electrode space discharge tube, a source of rectified alternating current, and means for energizing said tube from said source, said means comprising 80 a pair of impedance networks included in series between the terminals of said source, one of said networks comprising a resistance and a capacity in parallel, and the other of said networks comprising a resistance in parallel with a series combination of a resistance and a capacity, and said energizing means comprising also connections from the anode, the cathode, and the control electrode, respectively, to the outer terminal of the first mentioned network, the junction point of the two networks, and the junction point between the elements of the capacity-resistance combination in the second mentioned network, the capacity in said second network being included between the control electrode connection and the cathode. 85 90 95

3. In combination in a wave translating system, a three-electrode space discharge tube, having an anode, a control electrode and a 100 filamentary cathode, a source of undulatory current, a network comprising a resistance and a capacity in parallel, said network being included in a path between said anode and said cathode, a second network comprising a capacity in parallel with a divided resistance, said second network being included in a path between said control electrode and said cathode, and connections to the positive and negative terminals of said source respectively 105 from the outer terminal of said first network and from an intermediate point in said divided resistance, said networks being connected together in series, and their impedances being so proportioned that the ratio 110 of the potential drops therein due to the current from said source is equal to the amplification constant of the discharge tube. 115

4. In a wave translating system a combination in accordance with claim 3 characterized in that the said divided resistance includes the filamentary cathode of said tube. 120

In witness whereof, I hereunto subscribe my name this 7th day of May A. D., 1926.

FRANCIS X. RETTENMEYER.
